UNITED STATES PATENT OFFICE.

LEWIS H. GEBHART, OF DAYTON, OHIO.

FILING DEVICE.

1,198,435.

Specification of Letters Patent. Patented Sept. 19, 1916.

Application filed April 28, 1914. Serial No. 834,946.

To all whom it may concern:

Be it known that I, LEWIS H. GEBHART, a citizen of the United States, residing at Dayton, in the county of Montgomery and State of Ohio, have invented new and useful Improvements in Filing Devices, of which the following is a specification.

This invention relates to new and useful improvements in filing devices.

10 The principal object of my invention is to provide a collapsible paper index cabinet for the use of housewives, merchants and others who need a cheap and simple ready reference file. The wood and metal files now 15 in use are beyond the means of many persons who would welcome a paper cabinet. Being constructed of paper, or other light, inexpensive material, the cost of manufacture would be materially cheapened, while 20 its collapsibility would render the cost of delivery almost negligible. Its use in the household for containing recipes, patterns, etc. would make it invaluable to the housewife, by whom it could be secured at a 25 little more than the cost of postage.

Another object of my invention is to provide spear-head locking means which firmly unite the different parts of the cabinet together, making it practically impossible to 30 disassemble the latter after it is once set up.

One embodiment of my invention is illustrated in the accompanying drawings, of which—

35 Figure 1 is a perspective view of my improved paper index cabinet after it has been set up. Fig. 2 is a plan view of the blank as cut and scored to form the file. Fig. 3 is a detail view of one of the spear-head locking members in a position to be inserted into one 40 of the longitudinal slits. And Fig. 4 is a fragmentary view showing a side and end wall locked together by one of the spear-head members.

Throughout the specification and drawings, similar reference characters denote 45 corresponding parts.

Referring specifically to the drawings, Fig. 2 illustrates a blank made of paper, cardboard or other light material, and cut 50 and scored as follows: On this blank the numeral 1 designates the base of the file, and 2 and 3 its side walls, which are hingedly secured to the base along score lines 4 and 5 respectively. Hingedly secured to the 55 side wall 2, along score lines 6 and 7, are end walls 8 and 9 respectively. These end walls

8 and 9 contain, in their middle portions, longitudinal slits 10 and 11 respectively, which are preferably parallel with the score lines 6 and 7 and are provided for a purpose 60 to be hereinafter described. Hingedly secured to the side wall 3, along score lines 12 and 13, are flap portions 14 and 15 respectively. These flap portions extend a short 65 distance beyond their respective score lines and terminate in spear-head locking members 16 and 17 respectively. Each of said spear-head members has a pointed front end 18, and locking ears 19 and 20. Each pair 70 of locking ears 19 and 20 are hingedly secured to their respective spear-head member along score lines 21 and 22 respectively. It is thus possible to bend the locking ears 19 and 20 down upon their respective spear-head members to enable the latter to be 75 forced through the longitudinal slits 10 and 11 for a purpose to be hereinafter explained. Hingedly secured to the side wall 2, along a score line 23, is a top or cover 24. The cover 24 is provided with rectangular flange portions 25, 26 and 27, which are hingedly secured thereto along score lines 28, 29 and 30. When the file is set up, these flange portions may be turned about their respective score 80 lines, and united at their ends by stickers 31 85 or other suitable means (see Fig. 1). Hingedly secured to the base 1, along score lines 32 and 33, are guides 34 and 35 which serve a purpose hereinafter to be explained.

To form the upright file illustrated in 90 Fig. 1, the collapsible members hereinbefore referred to are folded about their respective score lines as follows. The guides 34 and 35 are moved to a vertical position about their respective score lines 32 and 33. 95 The side members 2 and 3 are then bent upwardly about their respective score lines 4 and 5, after which the end walls 8 and 9 are turned inwardly. The flap portions 14 and 15 are then bent inwardly in such a manner 100 that the spear-head members 16 and 17 may enter and be passed through their respective longitudinal slits 10 and 11 in the end walls 8 and 9. It is first necessary, however, to bend the locking ears 19 and 20 down 105 upon their respective spear-head members 16 and 17, before the latter can be forced through the longitudinal slits (see Fig. 3). After they have been forced through said slits, the said locking ears may be moved 110 outwardly by the fingers against the end walls 8 and 9. In this position they act as

flanges to completely lock the flap portions 14 and 15 to said end walls, from which they cannot be disengaged without tearing or mutilating the file. (See Fig. 4). It will thus be seen that my improved spear-head locking devices are readily adjusted, and absolutely efficient in maintaining the file in its assembled form. When the end and side walls have been thus united by the locking members 16 and 17, the file may be closed or opened by the hinged cover 24.

Adapted to be contained within the file just described, is a plurality of index members 36 supplied with suitable characters or designations 37, the front ones of which show above a concave edge 38 provided in the top portion of the side wall 3.

The end walls 34 and 35 act as suitable guides for the index members 36, as well as preventing the latter from coming in contact with the pointed locking ears 19 and 20 of the spear-head members 16 and 17. These guides also act as reinforcing means for the end walls 8 and 9 against which they rest.

The index members which I employ are cards, but they may be made of any suitable material and fashioned in any shape which will permit them to be readily adjustable between the guides 34 and 35 without departing from the spirit of my invention.

It will now be seen that I have provided a cheap, light and durable filing cabinet,

which may be readily assembled from its collapsed position for efficient service in the 35 household or other place where such a file is desired.

I do not wish to be limited to the details of construction and arrangement herein shown and described, and any changes or 40 modifications may be made therein to suit different conditions of use.

Having described my invention, I claim:

A collapsible filing device comprising a base, a pair of side walls hingedly secured 45 to said base along score lines, a pair of end walls hingedly secured to one of said side walls, a flap portion hingedly secured to each end of the other of said side walls, spear-head locking members carried by each flap portion to enter a longitudinal slit provided in each end wall, each spear head member having a pair of spear point ears adapted to be folded outwardly upon said side walls after said members have been 50 passed through the longitudinal slits, and a pair of guides hingedly secured to said base and adapted to be raised against said side and end walls.

In testimony whereof I have hereunto set 60 my hand this 25th day of April, 1914.

LEWIS H. GEBHART.
